HANDBAG

Frederick Lewis Parks, 6748 Renoir Drive 70806, and Henry Oscar Gaudet, 1737 Bellfort Drive 70815, both of Baton Rouge, La.

Continuation-in-part of abandoned design application Ser.
 No. 170,406, Aug. 9, 1971. This application Nov. 13, 1972, Ser. No. 305,978

Term of patent 14 years

Int. Cl. D3—01
 U.S. Cl. D87—3 C

FIG. 1 is a front elevational view of a handbag showing our new design;

FIG. 2 is a top plan view thereof;

FIG. 3 is a side elevational view;

FIG. 4 is a rear elevational view.

This is a continuation-in-part of copending application D. 170,406, filed Aug. 9, 1971 and now abandoned.

We claim:

The ornamental design for a handbag, substantially as shown and described.
